UNITED STATES PATENT OFFICE.

JOSHUA H. PRICE, OF DES MOINES, IOWA.

DESIGN FOR A HAT-PIN, BUTTON, CUFF-LINK, OR SIMILAR ARTICLE OF JEWELRY.

48,080.

Specification for Design.

Patented Nov. 2, 1915.

Application filed August 4, 1915. Serial No. 43,704. Term of patent $3\frac{1}{2}$ years.

To all whom it may concern:

Be it known that I, JOSHUA H. PRICE, a citizen of the United States, and resident of Des Moines, in the county of Polk and State of Iowa, have invented a new, original, and ornamental Design for Hat-Pins, Buttons, Cuff-Links, or Similar Articles of Jewelry, of which the following is a specification, reference being had to the accompanying drawing, forming a part thereof.

The figure shows a front elevation of a design for hat pins, buttons, cuff links, and

similar articles of jewelry embodying my invention.

I claim:

The ornamental design for a hat pin, button, cuff link, or similar article of jewelry, as shown.

Des Moines, Iowa, July 17, 1915.

JOSHUA H. PRICE.
